TELEPHONY

Frank de Fremery, Eindhoven, Netherlands, assignor to N. V. Philips' Gloeilampenfabrieken, Eindhoven, Netherlands

Application September 19, 1936, Serial No. 101,669
In Germany September 19, 1935

3 Claims. (Cl. 178—44)

My invention relates to telephony and more particularly to duplex communication systems using a forked circuit arrangement.

Forked circuit arrangements are commonly used in duplex communication systems for connecting a subscriber line to a transmitting channel and a receiving channel using a double line, such as the four-wire arrangement used in line telephony or in conference telephony. However, these channels may also be constituted partly by wireless transmitting installations and my invention includes such installations.

To overcome back-coupling such forked arrangements are provided with so-called line balances which should match as closely as possible the apparent resistance of the subscriber line; the degree of freedom from back-coupling depending upon the quality of these line balances. As in most cases such line balances do not fully meet the requirements, it has been suggested to increase the degree of freedom from back-coupling by adding back-coupling blocking means which, in duplex systems, serve to block one transmitting direction when speech current flows in the other transmitting direction.

The object of my invention is to overcome the above difficulties and to provide a forked circuit system having back-coupling blocking means, which system is completely free from back-coupling and does not employ line balances.

In accordance with my invention, I provide the system with two additional impedances which form with the input impedance of the transmitting channel and with the output impedance of the receiving channel, a bridge arrangement having as a diagonal the subscriber line in series with another impedance. With this arrangement, the alternating currents coming from the subscriber line produce equal and opposite voltages across the additional impedances, whereas the alternating currents coming from the receiving channel produce rectified voltages across both of the additional impedances; the A. C. voltages across the impedance connection in series with the subscriber line and those produced across the two additional impedances controlling the back-coupling barrier in opposite directions.

In order that my invention may be clearly understood and readily carried into effect, I shall describe the same more fully with reference to the accompanying drawing in which:

Figure 1 is a schematic wiring diagram of a conference telephone system embodying my invention, and

Figure 2 is a schematic wiring diagram of the bridge arrangement used in Fig. 1.

Referring to Fig. 1, the reference number 1 designates a conference room in which are located a microphone 2 and a loudspeaker 3 connected through a forked arrangement to the sub-

scriber lines 8 and 9. For this purpose the loudspeaker 3 is connected through conductors 6—6, to an amplifier 4 and hence through conductor 25 and an impedance 12 to the subscriber line 8, and through conductor 26 and an impedance 11 to point 24 connected to the subscriber line 9. Similarly, microphone 2 is connected through conductors 7—7 to an amplifier 5, and hence through a conductor 27 and the impedance 12 to the subscriber line 8, and through conductor 28 and an impedance 10 to point 24. As the construction of such amplifiers is well known, detailed discussion of the same is believed unnecessary.

The system also includes a back-coupling suppressor comprising a grid-controlled amplifying tube 13, and a relay 14 whose actuating coil is connected in the anode circuit of tube 13 with one terminal connected to the plate of the tube and its other terminal connected through a battery 31 to the cathode. The relay 14 has a normally-open contact 20 adapted to shunt the lines 6 and a normally-closed contact 21 adapted to shunt the lines 7.

Connected in series across the grid and cathode of tube 13 are two resistances 18 and 19 shunted by condensers 22 and 23 respectively. The resistance 18 is connected through a rectifier 16 to the secondary winding of a transformer 29 having a primary winding connected across the impedance 12. Similarly, resistance 19 is connected through a rectifier 17 to the secondary winding of a transformer 30 whose primary winding has its ends connected across impedances 10 and 11 and its center tap connected to point 24.

As indicated in Fig. 2, Z_s representing the input impedance of the transmitting circuit and Z_e representing the output impedance of the receiving circuit, form together with impedances 10 and 11, a bridge arrangement having a diagonal comprising the series connection of the subscriber lines 8 and 9 and the impedance 12. The impedances 10 and 11 are given such values that speech currents coming from the subscriber lines 8, 9, will produce equal and opposite A. C. voltages in the impedances 10 and 11, whereby no A. C. voltage will be applied to rectifier 17 and hence will cause no voltage drop across resistance 19. However, when the subscriber is talking at the end of line 8, an A. C. voltage is produced across impedance 12 and applied to rectifier 16 to thereby produce a D. C. voltage drop across resistance 18.

This voltage drop across resistance 18 negatively biases the grid of tube 13 to such an extent that the anode current is reduced to thereby release relay 14. With relay 14 released contact 21 shunts the lines 7 of the receiving circuit and contact 20 opens to remove the shunt from lines 6 of the transmitting circuit. The speech cur-

rents coming from the subscriber lines are then amplified by amplifier 4 and actuate the speaker 3.

If the microphone 2 is used, the speech oscillations thereof are amplified by amplifier 5, reach the forked arrangement and produce an A. C. voltage across impedances 10, 11 and 12. As appears from Fig. 2, the A. C. voltages across impedances 10 and 11 do not neutralize each other, but produce an A. C. voltage which is rectified by rectifier 17 to produce a D. C. voltage drop across resistance 18 to thereby bias the grid of tube 13 more positively. The A. C. voltage produced across impedances 12 by these speech oscillations is rectified by rectifier 16 and produces across resistance 18 a D. C. voltage drop which negatively biases the grid of tube 13. By giving the impedances 10, 11 and 12, the resistances 18 and 19, and the transformers 29 and 30, suitable electrical values, it can be insured that the voltage drop across resistance 19 is equal to or greater than the voltage drop across resistance 18 whereby the bias of the grid of tube 13 does not vary or become more positive. Under these conditions the relay 14 remains closed and contact 20 shunts the lines 6 of the transmitting channel whereas contact 21 is open to remove the shunt from lines 7.

From the above it appears that, when speaking on the subscribers' lines, the lines 6 of the transmitting channel are not shunted and the lines 7 are shunted to block the receiving channel, and that, when using the microphone 2, the lines 6 of the transmitting channel are shunted and the lines 7 of the receiving channel are open. In either case, any undesirable back-coupling is completely avoided.

While I have described my invention in connection with specific examples and applications, I do not wish to be limited thereto, but desire the appended claims to be construed as broadly as permissible in view of the prior art.

What I claim is:—

1. A duplex communication system comprising a subscriber line, a receiving channel and a transmitting channel connected to said subscriber line in a fork arrangement without the use of a line balance, a back-coupling suppressor for short-circuiting either the receiving or the transmitting channel, and means for controlling said back-coupling suppressor comprising an auxiliary impedance in series with the subscriber line and serving to produce a controlling voltage, a supplementary impedance in said receiving channel, a second supplementary impedance in said transmitting channel, said supplementary impedances being connected in series and serving to produce a controlling voltage, the alternating currents coming from the subscriber line producing equal and opposite voltages in said supplementary impedances, said supplementary impedances forming with the input impedance of the transmitting channel and the output impedance of the receiving channel a bridge arrangement having a diagonal comprising the subscriber line in series with said auxiliary impedance, means for rectifying the voltage produced across the auxiliary impedance to produce a rectified voltage which controls the suppressor in one direction, and means for rectifying the

voltage produced across the series-connection of the supplementary impedances to produce a rectified voltage which controls the suppressor in the opposite direction.

2. A duplex communication system comprising a subscriber line, a receiving channel and a transmitting channel connected to said subscriber line in a fork arrangement without the use of a line balance, a back-coupling suppressor for short-circuiting either said receiving or transmitting channel, and means for controlling said back-coupling suppressor comprising an auxiliary impedance in series with the subscriber line and serving to produce a controlling voltage, a supplementary impedance in said receiving channel, and a second supplementary impedance in said transmitting channel, said supplementary impedances being connected in series and serving to produce a controlling voltage, the alternating currents coming from the subscriber line producing equal and opposite voltages in said supplementary impedances, and the alternating current coming from the receiving channel producing additive voltages in said supplementary impedances, said supplementary impedances forming with the input impedance of the transmitting channel and the output impedance of the receiving channel a bridge arrangement having a diagonal comprising the subscriber line in series with said auxiliary impedance, means for rectifying the voltage across said auxiliary impedance to produce a rectified voltage which controls the suppressor in one direction, and means for rectifying the voltage across the series connection of the supplementary impedances to produce a rectified voltage which controls the suppressor in the opposite direction.

3. A duplex communication system for conference telephony comprising a receiving channel, a subscriber line, a transmitting channel, said receiving and transmitting channels being connected to said subscriber line in a fork arrangement without the use of a line balance, a back-coupling suppressor for short-circuiting either said receiving or transmitting channel comprising a grid-control tube, and a relay having an actuating coil connected in the plate circuit of said tube, and contacts in one position shunting said transmitting channel and in the other position shunting said receiving channel, and means for biasing the grid of said tube comprising an auxiliary impedance in said subscriber line, a supplementary impedance in said transmitting channel, a second supplementary impedance in said receiving channel, said supplementary impedances forming with the input impedance of the transmitting channel and with the output impedance of the receiving channel a bridge arrangement having a diagonal comprising the subscriber line in series with the auxiliary impedance, two resistances connected in series in the grid circuit of said tube, a rectifying circuit connecting one of said resistances across said auxiliary impedance, and a second rectifying circuit connecting the second resistance across the series connection of said supplementary impedances and including a transformer having a primary winding provided with a mid-tap connected between said supplementary impedances.
